UNITED STATES PATENT OFFICE

156,851

RECIPE CONTAINER OR SIMILAR ARTICLE

Robert Simons, Los Angeles, Calif., assignor to Shelly, Inc., Los Angeles, Calif., a corporation of California

Application August 27, 1946, Serial No. 132,880

Term of patent 3½ years

(Cl. D44—24)

To all whom it may concern:

Be it known that I, Robert Simons, a citizen of the United States, residing at Los Angeles, in the county of Los Angeles, State of California, have invented a new, original, and ornamental Design for a Recipe Container or Similar Article, of which the following is a specification, reference being had to the accompanying drawing, forming a part thereof.

In the drawings:

I claim:

The ornamental design for a recipe container or similar article, as shown.

ROBERT SIMONS.
